RESISTANCE-CAPACITANCE COUPLED AMPLIFIER

William A. Fitch, Schenectady, N. Y., assignor to General Electric Company, a corporation of New York

Application April 28, 1932. Serial No. 608,021

6 Claims. (Cl. 179—171)

My invention relates to amplifiers and more particularly to impedance or resistance-capacitance coupled amplifiers for operation over a wide range of audio and radio frequencies.

5 In television transmitters and receivers it is necessary to provide amplification for the frequency impulses which produce the television image. Such frequency impulses may range from an audio frequency of 20 cycles to a radio 10 frequency of 200,000 cycles or more. For the amplification of such frequencies which include both audio and radio frequencies, the ordinary resistance-capacitance coupled amplifier has been used, but the coupling capacitor introduces 15 a large phase shift at the low audio frequencies which has the effect of shifting the various lines of the television image so that the picture becomes distorted.

My invention has for one of its objects to provide 20 an amplifier with a resistor-capacitor means for neutralizing the phase shift introduced by the coupling capacitor.

The novel features which I believe to be characteristic of my invention are set forth with particularity in the appended claims. My invention itself, however, both as to its organization and method of operation, together with other advantages thereof, will be better understood by referring to the following description taken in connection with the accompanying drawing in which Fig. 1 illustrates a resistance-capacitance coupled amplifier embodying my invention; Fig. 2 is a schematic equivalent of the circuit shown in Fig. 1; Fig. 3 shows vectorially the phase shift 35 of the coupling capacitor; and Fig. 4 shows vectorially how my invention neutralizes the phase shift of the coupling capacitor.

Referring to the drawing, I have illustrated in Fig. 1 a resistance-capacitance coupled amplifier 40 having an input connected to the cathode and control element of an electron discharge device 1. The control element may be biased by a source of potential 2 connected between the cathode and the grid coupling resistor 3 which is connected to the control element. The anode of the electron discharge device is energized from a source of potential 4 through an anode coupling resistor 5. The anode is coupled to the control element of a second electron discharge device 6 45 by means of a coupling capacitor 7. The control element of the electron discharge device 6 is connected to a grid coupling resistor 8, and it may be biased by a source of potential 9 connected between the resistor 8 and the cathode. The anode 55 of the electron discharge device 6 is supplied by

current from a source of potential 10 through an anode coupling resistor 11. A coupling capacitor 12 is connected to the anode to provide an output circuit which is connected between the capacitor 12 and the cathode. A connection 13 provides a lead common to the cathodes of electron discharge devices 1 and 6, and the input and output circuits.

A capacitor 14 in series with a resistor 15 is arranged in parallel with the anode coupling resistor 5 to neutralize the phase shift introduced by the coupling capacitor. The resistor 15 and the capacitor 14 are so proportioned that the signal voltage component across the capacitor 14 is just sufficient to cause the signal voltage across the anode coupling resistor 5 to lag the same amount that the signal voltage across grid coupling resistor 8 leads the signal voltage existing across the anode and cathode of the electron discharge device 1. The electron discharge device 6 has a capacitor 16 and a resistor 17 connected across the anode coupling resistor 11 to neutralize the phase shift introduced by the coupling capacitor 12.

In Fig. 2 of the drawing I have shown a schematic diagram of a circuit equivalent to that shown in Fig. 1. The electron discharge device 1 may be considered as a source of alternating potential E_1 and the anode-to-cathode resistance of the device 1 is shown as R_1 . The anode circuit is represented by R_{15} in series with C_{14} , and R_5 in parallel therewith. The coupling capacitor C_7 is connected to R_5 which represents the grid circuit resistance of the electron discharge device 6.

The effect of the phase shift introduced by the coupling capacitor C_7 is shown in the vector diagram of Fig. 3. The voltage component across the resistor R_5 is equal to E_3 and the current I_6 , flowing in R_5 , is in phase with the voltage E_3 . This voltage E_3 and current I_6 may be shown vectorially as a horizontal line. The voltage E_{C7} across the coupling capacitor C_7 is in quadrature to the current I_6 flowing through the capacitor. The vectorial resultant of the voltages E_3 and E_{C7} is the voltage E_2 which lags the voltage E_3 by an angle θ . This represents the amount of phase shift which must be neutralized so that the voltage E_3 will be in phase with the voltage E_1 .

The vector diagram shown in Fig. 4 illustrates how the capacitor 14 and the resistor 15 neutralize the phase shift of the coupling capacitor 7. The voltage present across the resistor R_{15} is in phase with the current I_{15} flowing through it and may be plotted as a horizontal

line E_{R15} in phase with the current vector I_{15} . The voltage E_{C14} across the capacitor C_{14} is lagging the current I_{15} by 90° and thus is shown in quadrature to the voltage E_{R15} . The vectorial sum of the voltage E_{R15} and the voltage E_{C14} is equal to the total voltage across the resistor R_{15} and capacitor C_{14} which is the voltage E_2 . The current I_5 flowing through the resistor R_5 is in phase with the voltage E_2 . The current I_1 flowing through the resistor R_1 is equal to the vector sum of the current I_{15} and the current I_5 flowing through the parallel branches of the anode circuit. The voltage drop through the resistor R_1 developed by the current I_1 is equivalent to the voltage E_{R1} which is in phase with the current I_1 . The voltage E_1 impressed across the resistors R_1 , R_{15} and the capacitor C_{14} is equal to the vectorial sum of the voltages E_{R1} , E_{R15} , and E_{C14} existing across the various circuit parts.

20 The sum of the voltages E_{R15} and E_{R1} may be obtained as a vector shown as $E_{R15} + E_{R1}$ which is then vectorially added to the vector voltage E_{C14} to obtain the vector E_1 . By proper proportions of the resistor R_{15} and the capacitor C_{14} , the voltage E_2 may be caused to lag the voltage E_1 by an angle θ . As the voltage E_1 is displaced by an angle θ from the voltage E_2 the same amount as the voltage E_3 is displaced from the voltage E_2 and thus the voltage E_3 is in phase with voltage E_1 .

30 It is obvious that the voltage E_2 may be displaced from the voltage E_1 by any desired angle to neutralize the phase shift introduced by the coupling capacitor 7. My invention has the advantage of providing an amplifier for use over a range including audio and radio frequencies, with means for neutralizing the phase shift introduced by the coupling capacitor.

40 While I have shown and described my invention in connection with certain specific embodiments, it will, of course, be understood that I do not wish to be limited thereto, since it is apparent that the principles herein disclosed are susceptible of numerous other applications, and 45 modifications may be made in the circuit arrangements and in the instrumentalities employed without departing from the spirit and scope of my invention as set forth in the appended claims.

50 What I claim as new and desire to secure by Letters Patent of the United States, is:

1. In a resistance-capacitance coupled amplifier for operation over a wide range of audible and super-audible frequencies, the combination of a resistor in series with a capacitor connected 55 between the anode and cathode of an electron discharge amplifier of such magnitude that the phase shift introduced by the coupling capacitor is neutralized.
2. A resistance-capacitance coupled amplifier 60 arranged to operate over a wide range of audio and radio frequencies including an electron discharge device having an anode, a cathode, and a control element, a coupling resistor connected between said anode and said cathode, a coupling capacitor connected to said anode for connection to the control element of a succeeding electron discharge device, a resistor in series with a

capacitor and connected in parallel with said coupling resistor and having such magnitudes that the phase shift introduced by said coupling capacitor is neutralized.

3. A resistance-capacitance coupled amplifier 80 operating over a wide range of audio and radio frequencies including a pair of electron discharge devices each having a cathode, an anode and a control element, a coupling resistor connected between the cathode and anode of the first discharge device, a coupling resistor connected between the cathode and control element of the second discharge device, a coupling capacitor connected between the anode of one electron discharge device and the control element of the other of said electron discharge devices, said capacitor normally introducing a phase shift, a resistor in series with a capacitor arranged between the anode and cathode of said first electron discharge device in parallel to said coupling resistor and having such magnitudes that the phase shift introduced by said coupling capacitor is neutralized.

4. A resistance-capacitance coupled amplifier 100 for operation over a wide range of frequencies comprising audio and radio frequencies, said resistance-capacitance coupled amplifier including an electron discharge device having a cathode, an anode and a control element, an output circuit for said device including a coupling resistor connected to said anode and cathode, a capacitor connected to said anode for coupling said electron discharge device to the input circuit of a succeeding electron discharge device, and means connected in parallel with said anode coupling resistor and having a reactive component sufficient for neutralizing the phase shift introduced by said capacitor.

5. In combination, an electron discharge device, a load device, a coupling capacitor connected between said electron discharge device and said load device whereby the voltage supplied to said load device is shifted in phase with respect to the output voltage of said electron discharge device, and means connected in shunt to 115 said electron discharge device on the side adjacent to said coupling capacitor, said means producing a reactive component sufficient to neutralize said phase shift thereby to maintain the voltage on the load device in phase with the output voltage of said electron discharge device.

6. An audio and radio frequency amplifier comprising an electron discharge device having a cathode, an anode and a control element, a coupling resistor connected between said anode and 130 said cathode, a load circuit for said device, a coupling capacitor connected between said anode and said load circuit, said coupling capacitor normally introducing a phase shift between the signal voltage generated by the device and the signal voltage supplied to said load circuit, and a resistor in series with a capacitor connected between said anode and said cathode and having such magnitudes so as to produce a reactive component sufficient to neutralize the phase shift introduced by said output coupling capacitor.
